UNITED STATES PATENT OFFICE.

CARLETON P. RITCHIE, OF LOS ANGELES, CALIFORNIA, ASSIGNOR TO KLINCH-LATH CORPORATION, OF LOS ANGELES, CALIFORNIA, A CORPORATION OF CALIFORNIA.

WATERPROOF PLASTER BOARD AND METHOD OF PRODUCING SAME.

Application filed January 9, 1924. Serial No. 685,199.

To all whom it may concern.

Be it known that I, CARLETON P. RITCHIE, a citizen of the United States, residing at Los Angeles, in the county of Los Angeles, 5 State of California, have invented a new and useful Waterproof Plaster Board and Method of Producing Same, of which the following is a specification.

My invention relates to plaster board such 10 as is used in building construction. Plaster board is commonly produced by uniting one or more sheets of paper with an intermediate layer of plaster, the plaster adhering to the paper and forming a thin board which 15 may be used for exterior or interior purposes. In some cases the plaster board is nailed to suitable studding and is painted to form partitions and interior surfaces, being then known as wall board. In other cases it 20 is used as a base for stucco on the exterior of buildings or as a base for plaster or stucco on the interior of buildings. My invention is applicable to all of these purposes.

Many inventors have attempted to produce 25 a plaster board which is more or less impervious to moisture by using one or more layers of waterproof paper. This waterproof paper is made by impregnating an ordinary paper with tar or asphaltum. It 30 is rather difficult to produce a reliable plaster board in which waterproof paper is used on account of the fact that the waterproof paper, being water resistant, does not readily absorb the wet plaster and the bond 35 between the paper and the plaster after setting is not very good. Where unsized or untreated paper is used, the paper being water absorbent, readily allows the plaster to penetrate into the mesh of the paper and 40 a remarkably permanent and solid bond is produced between the plaster and the paper.

It is an object of my invention to provide 45 a plaster board which, when completed, is quite waterproof and in which the bond between the waterproof paper and the plaster is very good.

Further objects and advantages will be made evident hereinafter.

Referring to the drawings which are for 50 illustrative purposes only,

Fig. 1 is an elevation of the paper used, the paper being torn into three layers to show the construction thereof.

Fig. 2 is a section on a very much en-

larged scale through a portion of the paper 55 used.

Fig. 3 is a section on a full sized scale of the completed plaster board.

In the use of my invention I employ a 60 paper consisting of three layers 11, 12 and 13. The layers 11 and 13 are of ordinary paper, such as is used in the manufacture of boxes and for other purposes. This paper may be sized or not, but in any event it should be slightly water absorbent and preferably somewhat loose in texture. Incorporated in the paper between the layers 11 and 13 is a layer 12 which has been thoroughly impregnated with tar or asphaltum. Paper of this general character can be purchased 65 on the market and its method of manufacture is well understood.

In the production of my preferred form of plaster board, I employ this paper in the ordinary manner running it over rollers and incorporating a layer of wet plaster 14 between two layers 15 and 16 of the above described paper. The layers 11 and 13, being water absorbent, readily form a very complete bond with the plaster 14 as it sets, 75 either side of the paper being placed next to the plaster. In the ordinary practice of my invention I may use only one sheet of impregnated paper 15, the other sheet 16 being the ordinary paper. Or I may use 80 paper of the general form shown in Fig. 2 for both the layers 15 and 16. After forming the board, it is allowed to set, and is thoroughly hardened. It is then placed in a kiln, in which it is heated to a sufficient temperature to melt the impregnating material in the layer 12. This material as it melts 85 spreads to the layers 11 and 13, impregnating the same and thoroughly waterproofing 90 the entire surface of the board. 95

I claim as my invention:

1. A method of producing a waterproof plaster board which comprises: preparing a paper partially saturated with a waterproof substance, one surface of said paper being initially free from said substance; preparing a plaster board in which said untreated surface is in contact with the plaster which adheres readily thereto; and thereafter treating said plaster board to cause said waterproof substance to spread through said paper. 100

2. A method of producing a waterproof

- plaster board which comprises: preparing a paper partially saturated with a waterproof substance, one surface of said paper being initially free from said substance;
- 5 preparing a plaster board in which said untreated surface is in contact with the plaster which adheres readily thereto; and thereafter heating said plaster board to a sufficient temperature to cause said waterproof substance to spread through said paper.
- 10 3. A method of producing a waterproof plaster board which comprises: uniting a paper having a water absorbing surface
- 15 and a waterproof inner core with a layer of plaster, in such a manner that the plaster permeates and unites with the paper adjacent to said water absorbing surface; and thereafter heating the plaster board to cause
- 20 the waterproofing material in said water-

proof inner core to spread into the paper adjacent to said water absorbing surface.

4. A method of producing a waterproof plaster board which comprises: forming a plaster board with a paper which is partially impregnated with a waterproof substance; and thereafter treating the board to spread said substance through said paper.

5. A method of producing a waterproof plaster board which comprises: forming a plaster board with a paper which is partially impregnated with a waterproof substance; and thereafter heating said board to a temperature sufficient to melt said waterproof substance and to spread said substance through said paper.

In testimony whereof, I have hereunto set my hand at Los Angeles, California, this 3rd day of January, 1924.

CARLETON P. RITCHIE.
